UNITED STATES PATENT OFFICE.

WILLIAM H. PERRY, OF CONCORD, NEW HAMPSHIRE.

DESIGN FOR A MONUMENT.

SPECIFICATION forming part of Design No. 23,405, dated June 26, 1894.

Application filed May 19, 1894. Serial No. 511,871. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

The leading features of my design are the particular configuration of the shaft, and the ornamentation of said shaft and pedestal, and the character of the surfaces of different parts.

In the accompanying drawing I use figures and letters of reference to denote the various features of my design, and the style of finish.

The base 1, is oblong and has four vertical sides terminating at their tops in an obtuse frustum of a pyramid 2. The oblong pedestal 3, rests upon the frustum 2, and has four vertical sides terminating at their tops in an acute frustum of a pyramid 4. One or more sides of the said pedestal may be ornamented with a raised tablet 5, which is formed in a depression 6, cut on an incline, partly in the vertical side of said pedestal and partly in its frustum as shown. The shaft is also oblong and its sides 7 incline inward toward the top or upper portion thereof, and said shaft is ornamented at its bottom by the raised tablets 8, their upper edges being beveled as shown, and those on the longest sides of said shaft for the greater portion form an arch 9, terminating at its ends in semi-domical projections 10, which form the corners of said shaft and meet similar semi-domical projections 11—formed upon the upper edges of

the tablets 8, at the shorter end of said shaft. The top of the shaft is ornamented with raised tablets 12, the lower edges of which are provided with corner domical pendants 13, in 40 which appear the horizontal grooves 14. The upper edges of the tablets 12, have corner vertical projections 15, scalloped on top as at 16, and those on the longer sides of said shaft have vertical projections 17, at a point midway 45 from either end, which are also scalloped as at 18, on their tops. From the upper edges 19, of said tablets 12, the shaft terminates in a frustum of a pyramid 20, upon the top of which is formed a low plate piece 21, the edges 50 of the longest sides of which are chamfered as seen at 22.

One or both the longest sides of the shaft 7, are ornamented with a tablet 23, formed flush with said shaft, and distinguishable by 55 a border line of the configuration shown at 24, and by reason of the character of their finish which is polished work and denoted by the letter A. The other styles of finish are 60 designated by the letters B, C, the former representing hammered work, and the latter, rock work.

Having described my new design, what I claim is—

The design for a monument substantially 65 as herein shown and described.

In testimony whereof I affix my signature in presence of two witnesses.

WILLIAM H. PERRY.
